UNITED STATES PATENT OFFICE.

ROBERT A. WILSON, OF DALLAS, TEXAS, ASSIGNOR TO THE GUIBERSON CORPORATION, OF DALLAS, TEXAS, A CORPORATION OF DELAWARE.

PUMP-ROD GUIDE.

Application filed May 19, 1925. Serial No. 31,287.

This invention relates to new and useful improvements in pump rod guides.

The object of the invention is to provide in conjunction with a pump rod joint, an improved guide possessing certain advantageous features.

A particular object of the invention is to provide a guide which may be readily applied or removed and which is retained in place by the coupled members of the joint.

A further object is to provide a guide which may be mounted either to rotate or which may be made fast and held against rotation.

Another object of the invention is to provide the guide with helical vanes which not only form wearing members but act to impart rotation to the guide when the rod is reciprocated.

A particular object of the invention is to mount a guide with helical ribs rigidly on the pump rod so that by swiveling the polish rod said pump rod will be rotated upon its down stroke thus doing away with a rotor.

A still further object of the invention is to provide amplified bearing surfaces on the vanes, whereby the period of service of the guide is lengthened.

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is an elevation of a pump rod joint equipped with a guide constructed in accordance with my invention,

Fig. 2 is a vertical sectional view of the same,

Fig. 3 is a plan view of the guide,

Fig. 4 is an elevation of another form in which the invention may be carried out,

Fig. 5 is a plan view of the latter, and

Fig. 6 is a diagrammatical view showing a pump rod with my improved guide thereon.

In the drawings the numeral 10 designates the pin member of a rod joint and 11 the box member. The member 10 has a depending pin 12 which may be of the mutilated thread type, or of the continuous thread type now in common use.

The pin is inserted in the threaded well

13 of the box 11. The member 10 has a threaded socket 10' for connection with the upper section of the rod; while the member 11 has a socket 11' in its lower end for receiving the lower section of the rod. The box has a flat edge 14 at its upper end and the pin member 10 has an outwardly directed annular shoulder 15 overhanging the edge 14.

The box 11 has a reduced cylindrical portion 16 extending from a shoulder 17 to the edge 14. A guide sleeve 18 of bronze or other suitable material is snugly fitted on the portion 16 so as to rest on the shoulder 17. This sleeve preferably has its outer surface flush with the outer surface of the members 10 and 11 and extends either to the shoulder 15 or just short of the same. Where the sleeve is to rotate it terminates short of the edge 14 so as not to be engaged by the shoulder 15, but if it is intended to fasten the guide on the portion 16 it is engaged by the said shoulder 15.

The sleeve is provided with helical vanes or ribs 19 extending radially from its top to its bottom and given the desired pitch. The helical vanes have several advantages over perpendicular ribs, such as increased wearing surface and a better distribution of the wear. If the guide is mounted to rotate, by impact upon the liquid during the down pump stroke, and wear on the inner walls of the tubing will be more evenly distributed.

It will be seen that if the sleeve is loosely mounted on the member 11 it will rotate without rotating the rod, but if it is made fast on the joint and the polish rod is swiveled, as is shown in Fig. 6, then said guide will rotate the pump rod on the down pump stroke. Upon the up pump stroke the liquid will move with the guide, thus not rotating the latter. Where the guide is used to rotate the rod the use of a rotor for this purpose is eliminated and a saving effected.

In Figs. 4 and 5 another form of guide is shown. The sleeve 18 is formed with helical vanes 20 extending radially from the bottom to the top of the sleeve. These vanes have bearing shoes 21 on their outer edges somewhat wider than the vanes and provided with amplified bearing faces 22. The vanes are given such a pitch that the upper end of one shoe (Fig. 4) overhangs the lower end of the next shoe, thus giving the effect of a

cylindrical bearing surface completely surrounding the guide, when it is reciprocated and making for even wear.

It is of course understood that the function of the guide is to keep the joint centered in the tubing and to protect the joint from wear; the wear being taken by the guide. When the guide becomes worn the members 10 and 11 are uncoupled and the guide re-
10 placed in an easy and expeditious manner.

Various changes in the size and shape of the different parts, as well as modifications and alterations, may be made within the scope of the appended claims.

15 What I claim, is.

1. In a pump rod joint and guide, the combination of a pair of joint members coupled together, a guide sleeve into which the members are inserted from each end and
20 which encloses the coupled portions of said members, and helical vanes on the sleeve extending longitudinally thereof, each of said members having a portion at the adjacent end of the sleeve for confining the
5 sleeve against longitudinal displacement.

2. In a pump rod joint and guide, a box

member having a reduced portion with an outwardly directed shoulder at its base, a sleeve fitting on the reduced portion of the box member and supported on said shoulder, helical vanes on said sleeve extending outwardly of said shoulder, a pin member having engagement in the box member within the sleeve, and a retaining shoulder on the pin member overhanging the upper end of the sleeve and engaging the upper end of the box.

3. In a pump rod joint and guide, a box member having a reduced portion with an outwardly directed shoulder at its base, a sleeve fitting on the reduced portion of the box member and supported on said shoulder, helical vanes on said sleeve extending outwardly of said shoulder, a pin member having engagement in the box member within the sleeve, and a retaining shoulder on the pin member overhanging the upper end of the sleeve and engaging the upper end of the box, the sleeve throughout its length being substantially flush with the shoulders.

In testimony whereof I affix my signature.
ROBERT A. WILSON.
